UNITED STATES PATENT OFFICE.

SAMUEL E. WRIGHT, OF RANGER, TEXAS.

PORTABLE FORGE.

1,369,869.

Specification of Letters Patent. Patented Mar. 1, 1921.

Application filed August 19, 1919, Serial No. 318,547. Renewed January 18, 1921. Serial No. 438,262.

To all whom it may concern:

Be it known that I, SAMUEL E. WRIGHT, a citizen of the United States, residing at Ranger, in the county of Eastland, State of Texas, have invented a new and useful 5 Portable Forge; and I do hereby declare the following to be a full, clear, and exact description of the invention, such as will enable others skilled in the art to which it applies 10 pertains to make and use the same.

The invention relates to forges and has for its object to provide a portable forge particularly adapted for use in oil well drilling operations wherein it is necessary to have 15 a forge which will be capable of being quickly and easily knocked down and stored in compact form as the oil drilling operations move from point to point.

A further object is to provide a forge 20 comprising a base having a marginal flange, and to provide upstanding sides for forming a fire receiving receptacle. Also to provide interlocking means whereby the corners formed by the sides may be securely locked 25 together, thereby preventing the collapse of the sides.

With the above and other objects in view the invention resides in the combination and arrangement of parts as hereinafter set 30 forth, shown in the drawings, described and claimed, it being understood that changes in the precise embodiment of the invention may be made within the scope of what is claimed without departing from the spirit 35 of the invention.

In the drawings:—

Figure 1 is a perspective view of the forge.

Fig. 2 is a top plan view.

Fig. 3 is a sectional view taken on line 3—3 of Fig. 2.

Fig. 4 is a sectional view taken on line 4—4 of Fig. 2.

Fig. 5 is a detail perspective view showing the adjacent corners of the sides in position for locking and interengaging.

Referring to the drawings, the numeral 1 designates a forge which comprises the base 2 and the body 3, said body comprising 50 sides 4, front and rear ends 5 and 6. The front and rear ends 5 and 6 are provided with right angle vertically disposed flanges 7, which flanges are adapted to receive the sides 4 and engage them on their outer surfaces. Sides 4 are also provided with flanges 55 for engaging the front and rear ends 5 and 6,

which flanges are designated by the numeral 8. The front and rear ends 5 and 6 adjacent the flanges 7 are provided with right angle integral members 9, which members engage over the upper ends of the flanges 8, thereby allowing the body portions of the sides 4 to be disposed between said right angle members and the flanges 7. By so positioning the right angle members, 65 it will be seen that the inward collapsing of the sides 4 and the ends 5 and 6 will be prevented. It will also be seen that the body member may be easily assembled by placing the parts of the adjacent corners 70 in the position shown in Fig. 5 and forcing the end members downwardly so that the right angle members 9 will engage over the flanges 8.

The base 2 is provided with a marginal 75 flange 10, which flange is adapted to fit the side and end walls of the body member after said body has been assembled and placed in position on the base. Base 2 is provided with legs 11 whereby the forge as a whole 80 will be supported spaced from the ground when in use.

Sides 4 and the rear end 6 are preferably reinforced by angle irons 12 which angle irons are secured to the upper marginal 85 edges of said parts by means of rivets 13. The front wall 5 is cut away as at 14 and part of the material cut away is folded downwardly and bent around a transversely disposed strip thereby forming a ledge on 90 which drills and the like may rest when the same are being heated, for resharpening. The interior of the portable forge is to be built up with the usual form of fire clay or fire brick construction.

From the above it will be seen that a portable forge is provided, which may be easily moved from place to place and so collapsed and stored as to take up very little room.

The invention having been set forth what 100 is claimed as new and useful is:—

1. A portable forge comprising a base member, said base member being provided with an upstanding marginal flange, a body member disposed on the base member and 105 maintained in position by said marginal flange, and comprising side and end pieces, said side and end pieces being provided at their ends with right angle flanges, the flanges carried by the end pieces being disposed outside of the ends of the side pieces, 110 the flanges carried by the side pieces engag-

ing the inner faces of the end pieces and L-shaped lugs carried by the upper edges of the end pieces and spaced from their right angle flanges whereby the downwardly extending portions of the L-shaped pieces will engage over the upper edges of the flanges at the ends of the side pieces thereby locking the sides between said downwardly extending portions and the flanges carried by the ends of the end pieces.

2. A portable forge comprising a base member, said base member being provided with an upstanding marginal flange, a body member disposed on the base member and maintained in position thereon by said mar-

ginal flange, said body member comprising side and end walls having right angle flanges, said flanges interengaging each other and L-shaped lugs carried by the upper marginal edges of the end pieces and adapted to engage over the flanges of the side pieces for locking the side and end pieces rigidly together.

In testimony whereof I have signed my name to this specification in the presence of two subscribing witnesses.

SAMUEL E. WRIGHT.
